UNITED STATES PATENT OFFICE

121,603

DESIGN FOR A COMBINED VEHICLE RADIO
ANTENNA, VENTILATOR, AND REAR VISION
MIRRORCharles D. Thomas, Batavia, N. Y., assignor of
one-half to Herbert J. Baer, Hamburg, N. Y.

Application December 16, 1939, Serial No. 88,937

Term of patent 14 years

To all whom it may concern:

Be it known, that I, Charles D. Thomas, a citizen of the United States, residing at Batavia, in the county of Genesee and State of New York, have invented a new, original, and ornamental Design for a Combined Vehicle Radio Antenna, Ventilator, and Rear Vision Mirror, of which the following is a specification, reference being had to the accompanying drawing, forming part thereof.

In the accompanying drawing:

Fig. 1 is a perspective view of a combined vehicle radio antenna, ventilator, and rear vision mirror viewed from the front thereof.

Fig. 2 is a side elevational view of the same.

Fig. 3 is a top plan view of the same.

Fig. 4 is a front end elevational view of the same.

Fig. 5 is a rear end elevational view of the same.

I claim:

The ornamental design for a combined vehicle radio antenna, ventilator, and rear vision mirror, as shown.

CHARLES D. THOMAS.
